C. F. Brown.

Ordnance.

No 13,249.

Patented July 17, 1855.

UNITED STATES PATENT OFFICE.

CHAS. F. BROWN, OF WARREN, RHODE ISLAND.

IMPROVED MODE OF MOUNTING ORDNANCE.

Specification forming part of Letters Patent No. 13,249, dated July 17, 1855.

To all whom it may concern:

Be it known that I, CHARLES F. BROWN, of Warren, in the county of Bristol and State of Rhode Island, have invented a new and useful Improvement in Ordnance; and I do hereby declare that the following is a full, clear, and exact description of the same, reference being had to the accompanying drawings, forming part of this specification, in which—

Figure 1 is a side view of a gun mounted according to my invention, the carriage being shown in section. Fig. 2 is a plan of the same with the carriage in section.

Similar letters of reference indicate corresponding parts in both figures.

This invention relates to the construction of carriages for and method of mounting cannons and other ordnance in ships, forts, and land and floating batteries. Its object is to close, as nearly as possible, the ports or embrasures all around the piece, so as to prevent the entrance of an enemy's shot or other projectiles, and also to prevent the smoke being driven back in sufficient quantities to inconvenience the gunners and their attendants, but at the same time to allow the direction of the piece to be varied to the same extent as it can be when mounted in the usual way upon carriages of the usual construction.

The carriage of the gun consists of a frame, A, of cast-iron or other metal, made externally of spherical, spheroidal, or cylindrical form, or of any other form partaking of the character of those. It is provided with two pivots or journals, a a, to form a vertical axis, upon which it is capable of turning within the port or embrasure E in the side of the battery B, said port or embrasure being of such form that the carriage A closes it, but turns easily therein. The bearings b b for the pivots or journals are secured firmly to the side of the battery—one above and the other below the port or embrasure. The gun D passes through an opening, c, in the carriage A, and its trunnions g g rest in horizontal bearings, so made in the sides of the said opening that their axis intersects the axis of the carriage, and stands at right angles to the center of the opening c, which opening should be of such form as to allow the angle of the gun to be varied in a ver-

tical direction as much as may be desired, to suit the altitude and distance of the object to be aimed at. This opening may have a suitable space in the form of a narrow slit in the upper part, through which to take the sights; but otherwise the central part of it may fit almost closely round the piece. Springs d d should be applied in suitable cavities in rear of the trunnions, as shown in Fig. 2, to receive the force of the recoil when the discharge of the gun takes place. The gun is to be inserted in the carriage from behind, suitable slots being made leading from the back of the opening c to allow the trunnions to slide into their bearings. These slots also serve to receive the springs d d, which are confined in their places by stopping up the backs of the slots with plugs e e, which require to be firmly secured by keying, bolting, or other means.

Below the opening c there is a tail-piece, m, attached rigidly to or cast with the carriage A, to receive the screw f, by which the breech of the gun is raised and lowered to vary the angle of the gun vertically. Those parts of the sides or walls of the battery surrounding the port or embrasure should be no thicker than is necessary for a proper degree of strength, as too great a thickness would too much limit the horizontal swinging movement of the gun, so that it will be well to construct those parts of plates of wrought-iron, which may be of sufficient thickness to be shot-proof without interfering with the working of the gun, which may have a wider range than a gun mounted in any other way.

Although the carriage A may be of cylindrical or any other circular form, it is preferable to make it spherical or spheroidal, as that form will enable it to deflect a ball or projectile striking it at almost any point.

What I claim as my invention, and desire to secure by Letters Patent, is—

Mounting a cannon or any other piece of ordnance, substantially as herein described, in a carriage, A, of spherical, spheroidal, or other circular form externally, which carriage is arranged to close the port or embrasure through which the piece works, but to turn freely therein in a horizontal or nearly hori-

zontal direction, and which has an opening, c, within it of suitable size and form to receive the gun and to allow it the necessary upward and downward swinging movement on its trunnions, whereby an efficient protection is afforded against the entrance of an enemy's shot or other projectiles, and the

smoke of the discharge is excluded, and at the same time a desirable range in a lateral and vertical direction is maintained.

CHARLES F. BROWN.
